[57] CLAIM

The ornamental design for a stringed instrument head,
as shown and described.

DESCRIPTION

FIG. 1 is a front elevational view of a stringed instrument head showing my new design;

FIG. 2 is a view like FIG. 1 of a modified form of a
stringed instrument head showing my new design
whereon a contrasting inlay is included;

FIG. 3 is a left side elevational view; and

FIG. 4 is a rear elevational view.

FIG. 1.

FIG. 3.

FIG. 4.

FIG. 2.
